VAPOR ELECTRIC DEVICE

Joseph H. Cox, Forest Hills, Pa., assignor to Westinghouse Electric & Manufacturing Company, East Pittsburgh, Pa., a corporation of Pennsylvania

Application September 4, 1941, Serial No. 409,502

2 Claims. (Cl. 250—27.5)

My invention relates to a vapor electric device and, particularly, to an anode and shield assembly for such a device.

This application is a continuation-in-part of my application Serial No. 345,083, filed July 12, 1940.

In the operation of vapor electric devices, it has been found that if shields are provided between the anode and the active cathode surface so that the anode is optically obscured from the active cathode area, a reduction of arc backs is normally secured. However, this shield sometimes increases the pickup voltage necessary to establish the current carrying arc between the anode and the cathode so that it is desirable to provide suitable passages whereby at least a small amount of cathode vapor will pass into the vicinity of the anode.

Certain experiments have demonstrated that the condensing efficiency of the cooled condensing surface for condensing mercury vapor is materially improved if the condensing surface is bathed by the arc plasma in the converter.

The anode and shield assembly according to my invention is arranged to secure the benefit of these and other operating conditions.

The anode is of a so-called streamline shape having a substantially cylindrical base portion and sloping sides converging toward a tip of less cross-sectional area than the base. The anode is substantially enclosed by a shield member which conforms generally in shape to the anode, the end of the shield in proximity to the anode is substantially closed to prevent the blast of highly ionized cathode vapor from entering the anode space, but is provided with suitable baffled openings to admit sufficient vapor to facilitate the pickup of the current carrying arc between the cathode and anode.

The shield is provided with arc passages on the side portions so that the sides of the anode become the active anode face, so that the arc flowing from the side of the anode passes adjacent the side walls of the device and the arc plasma bathes the condensing surface improving its condensing efficiency. The converging shield also provides an enlarged space to facilitate the flow of the highly ionized cathode blast to the condensing surface.

It is an object of my invention to provide a converter in which the anode is suitably shaped to provide a large working surface, and which is provided with a suitable shield to exclude a major portion of the highly ionized vapor emanating from the cathode and to provide such

formations that the arc plasma will sweep adjacent the condensing surfaces, and thus improve the operating characteristic of the converter.

Other objects and advantages of my invention will be apparent from the following detailed description taken in conjunction with the accompanying drawings, in which:

Figure 1 is a sectional elevation of a vapor electric device according to my invention; and

Fig. 2 is a similar view of a preferred construction according to my invention.

The vapor electric device according to my invention comprises a suitable container herein illustrated as a metallic vessel 1. In the bottom 15 of the vessel 1 is a suitable pool 2 of a vaporizable reconstructing cathode material, such as mercury, or mercury amalgam. In order to restrict the active cathode area 3 to a predetermined portion of the cathode pool 2, a suitable barrier 4, usually a quartz ring, is anchored by suitable means 5 to the bottom of the cathode container.

In order to initiate the cathode spot, a make-alive device 6 is positioned in contact with the active cathode surface 3 of cathode 2. A suitable lead-in connection 7 is carried through the wall 20 of the container 1 by means of an insulating bushing 8.

Cooperating with the cathode 2 is an anode 10 30 preferably of graphite suspended on a suitable anode stem 11 which is held in insulated relation to the container 1 by means of a suitable insulating bushing 12. In order to provide a large effective working surface, the anode 10 is provided with a substantially cylindrical base 13 and a tip portion 14 of substantially frusto-conical or tapering cross-section converging in the direction of the cathode 2. At least that portion of the stem 11 which is in contact with the anode 10 is constructed of a conducting material 35 which is not dissolved by hot carbon.

A shield member 15, preferably composed of graphite, is suspended in insulated relation to the anode 10 and the container 1 by means of suitable insulating studs 16. The shield member 45 15 preferably conforms substantially in shape to the shape of the anode 10 and is placed as close thereto as is mechanically convenient. The converging portion of the shield enclosing the tip 14 of the anode 10 provides a tapered vapor space 17 50 through which the blast of highly ionized vapor from the cathode 2 may pass in traveling from the cathode to the condensing surface with a minimum increase in vapor pressure. The side portions of the shield are provided with suitable arc passages 18. The passages 18 are preferably 55

drilled holes in the side of the graphite shield 15 and are of such dimensions and so located that no part of the anode is optically exposed to the active cathode area 3 through the arc passages 18. As the arc passages 18 are substantially lateral of the working face of the anode 10, the current carrying arc passing between the cathode 3 and anode 10 sweeps adjacent the condensing surfaces so that the condensing surface is bathed in the arc plasma, thereby greatly increasing its efficiency.

That portion 19 of the shield 15 in proximity to the cathode 3 is substantially closed, but in order to admit sufficient cathode vapor to allow easy pickup of the current carrying arc, a suitable opening 20 is made in the end 19 of the shield 15 and a suitable baffle 21 provided in spaced relation to the opening 20 so that no part of the anode 10 is optically exposed to the active cathode area 3 through the vapor passage 20.

In the operation of rectifiers, it is found that the parts directly in contact with the arc stream operate at a temperature of the order of 1000° C. and as iron, many iron alloys and other metals have the property of dissolving in carbon at this temperature, considerable difficulty has been experienced in properly securing together the various graphite parts comprising an anode shield. Of the base metals, copper and nickel have the property of withstanding the dissolving activity of hot carbon. Copper is undesirable in the portions of the converter having a high mercury content such as the region traversed by the cathode vapor blast, therefore I have heretofore used screws 26 of nickel to secure the baffle 21 to the end 19 of the shield.

The nickel, however, is sputtered away by the arc so that not only is the fastening made insecure, but in certain applications having a high load factor the sputtered nickel contaminates the make-alive electrodes and interferes with the normal operation of the device. Therefore, I prefer to utilize a construction having no metal parts exposed to the arc stream as shown in the modification according to Fig. 2.

In the preferred construction, the vapor passages in the end 19 of the shield 15 are constructed in the intact shield material. I prefer to construct the passages by making a recess 30 then machining or under-cutting to form an enlarged base 31 in the recess and drilling a plurality of holes 32 offset with relation in the recess 30, the size of the holes 32 and depth of the offset being of such proportions that no part of the anode 10 is directly exposed to the active cathode area 3 through the openings 30—31—32.

Preferably the closed end portion 19 of the shield 15 is of such size with respect to the active cathode area 3 and the slope of the tapered side of the shield 15, that the blast of highly ionized vapor does not impinge on the openings 18 but sweeps past to the condensing surface through the enlarged space 17 without materially increasing the vapor pressure at any point in the device.

The tapered space 17 also provides an arc space increasing in cross-sectional area in the direction of the cathode which permits the passing of the arc without crowding.

If desired, a suitable connection 22 may be made to the shield 15 and carried through the container wall by means of an insulating bushing 23.

Preferably, liquid cooling devices, such as cooling coils 24, are provided for the condensing surface or any other portion of the device which it is desired to cool. In order to improve the appearance of the device, a suitable jacket 25 is applied to cover up the cooling coils 24 or other irregular surfaces of the device.

While for purposes of illustration I have shown and described a specific embodiment of my invention, it will be apparent that changes and modifications can be made therein without departing from the true spirit of my invention or the scope of the appended claims.

I claim as my invention:

1. A mercury vapor valve comprising a container, a mercury cathode in said container, means for initiating a cathode spot on said cathode, means for determining the active cathode area, a streamlined anode supported in spaced relation to the cathode, a graphite shield enclosing said anode and conforming in shape thereto for providing an arc passage increasing in cross-sectional area in the direction of the cathode, a plurality of arc passages in the sides of said shield whereby the arc plasma is brought into proximity with a large portion of the container wall, an opening in the end of the shield at a point exposed to the cathode and a baffle covering said opening.

2. In a vapor electric device, an anode and shield assembly comprising an anode head having a substantially cylindrical base portion, and a substantially frusto-conical tip portion, a graphite shield spaced from and substantially conforming in shape to the anode, a plurality of arc passages in said shield in proximity to the sides of the anode, an opening in the end of the shield in proximity to the end of the anode and a baffle covering said opening.

JOSEPH H. COX.
